BLAST BURNER NOZZLE

Edward J. Haedike, Chicago, Ill., assignor to National Machine Works, Chicago, Ill., a corporation of Illinois

Application January 16, 1941, Serial No. 374,715

2 Claims. (Cl. 158—109)

The invention relates to nozzles for blast burners such as are used for the combustion of high pressure mixtures of gaseous fuel and air. In such high pressure or blast burners, the velocity of the gas-air mixture, discharging from the burner, so far exceeds the normal rate of flame propagation as to make it essential to provide some means associated with the burner nozzle for stabilizing the ignition point of the flame. Otherwise, so-called "blow-off" will occur or, even worse, if the furnace temperature is below the ignition temperature for the gas-air mixture, ignition may not occur at all, with the result that the furnace or the like is filled with dangerous explosive mixture of gas and air.

Though various expedients have heretofore been used for preventing blow-off in blast burner nozzles of the type indicated, all of them have some one or more objectionable characteristics. For example, many of them entail the use of a pocketed baffle to confine a fringing or piloting flame, supplied with a suitable gas-air mixture. With such a pocketed baffle arrangement there is a tendency to retain products of combustion in the vicinity of the ignition zone, but any such retention defeats the whole purpose of the arrangement since carbon dioxide is one of the best of all inhibitors of combustion for gas-air mixtures. Similarly, if the fuel is a high hydrogen content gas, which is relatively fast burning, the ignition and combustion of the piloting fringe in the pockets defined by the baffle may, in many instances, produce local temperatures so severe that they will damage or destroy adjacent portions of the nozzle.

The general aim of the present invention is to overcome the defects noted with respect to the prior devices, and to afford a blast burner nozzle which is characterized not only by its ability to maintain combustion without "blowing," under even high supply pressures, but which also has great durability under even extremely severe conditions of usage.

More specifically, it is an object of the invention to provide a nozzle of the class indicated embodying a baffle arrangement defining a short combustion tunnel or chamber which coacts in a novel manner with the main port and fringing-flame ports, of the nozzle, to assure stability of combustion under a wide variety of gas-air pressure conditions.

Further objects and advantages of the invention will become apparent as the following description proceeds, taken in connection with the accompanying drawing in which:

Figure 1 is an end view, taken from the outer end, of a blast burner nozzle embodying the invention.

Fig. 2 is a longitudinal sectional view of the nozzle, taken substantially along the line 2—2 in Fig. 1.

While the invention is susceptible of various modifications and alternative constructions, I have shown in the drawing and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

In the instant embodiment of the invention, the nozzle shown comprises a cast metal body 10 of polygonal cross section, cored out to form a longitudinally extending gas-air mixture supply chamber 11. This chamber has an open outer end, which is tapped as indicated at 12 for connection to a suitable supply pipe (not shown) through which a mixture of combustible gas and air is supplied under pressure. The chamber 11 tapers longitudinally inward and terminates in a main port or throat 14 formed in a frustoconical eminence 15 on the outer end of the body 10. It will be observed that the port 14 is of large cross sectional area to accommodate a large volume of gas-air mixture, and it is so dimensioned, relative to the shape and dimensions of the supply passage 11, that the gas-air mixture issues from it at high velocity, in fact at a velocity well in excess of the normal rate of flame propagation for the mixture.

To form a stabilizing fringe of flame circumferentially about the main port 14, a plurality of auxiliary ports 16 are led from the supply chamber 11. These ports 16 are of small or restricted cross section as compared to the main port 14.

To form a combustion chamber or recess 17 in the end of the burner body, an annular baffle ring 18 is provided, being formed, in the present instance, as an integral part of the body 10. One key feature of the combustion chamber shape is that its inner side walls are contoured so as to converge inwardly, smoothly, to an end opening 19 which is of smaller diameter than the inner end of the chamber although slightly larger than the diameter of the main port 14. As to the smooth contour of the inner face of this chamber 17, observe particularly that it is entirely free of any undercuts or pocketing. Furthermore, the root of the groove, defined between the eminence

15 and the baffle ring 18, is smoothly curved so that there is also no pocketing or undercutting in that area. In other words, the opposed side faces of the eminence 15 and baffle 18 merge smoothly in the root of the groove between them. As a consequence, there is no undercut or pocket which could trap products of combustion.

It is also to be observed that the auxiliary ports 16 slant outwardly, from the longitudinal center line of the body 10, toward the curved inner face 5 of the baffle 18. Accordingly, the small streams of gas-air mixture emerging from the ports 16 sweep or scrub out along the inner face of the baffle as they burn and are bent inward, by the curvature or taper of the baffle face, toward the main body of gas-air mixture, streaming from the large port 14.

On the other hand, the high velocity gas-air mixture issuing from the main port 14 converges slightly, forming a vena contracta about an inch from the mouth of the port 14. The outer portion of the issuing pencil of gas-air mixture from the main port is thus ignited by the surrounding fringe of flame from the ports 16, the latter being slowed down by the scrubbing action on the inner face of the baffle ring 16, as heretofore noted. This results in a temperature within the combustion chamber 17 of the order of 2800° F. The high velocity main jet burns progressively inward and forward from the face of the burner. It will thus be seen that the piloting fringe of flame creates a temperature within the chamber 17 which stabilizes the base of ignition of the main jet, and accordingly, "blowing" of the flame away from the nozzle is obviated. In fact, the present nozzle is capable of utilizing, without "blow-off," gas-air mixtures at in excess of seventy per cent greater pressures than can be similarly accommodated in many prior nozzles designed for flame retention.

Not only is the mixture effectually ignited and the flame stabilized, but in addition a free exit for the products of combustion is afforded. Though the contour of the baffle confines the fringing flames (from the ports 16) in a lateral direction and causes them to converge inwardly toward the main stream of fuel, it does not pocket or positively confine them, or their products of combustion, against final escape.

Also of note is the massive character of the baffle ring 18 in its outer portion, this being accomplished in part by the very shape of its inner surface. This thickness of metal in the outer edge of the baffle ring makes it possible to cast the nozzle from low cost gray iron, as distinguished from high cost heat-resistant alloys, because of the high rate of heat dissipation accomplished. This is a matter of vital importance in many installations in achieving a long useful

life for the nozzle. It is often impractical in furnace installations to protect the nozzle from radiant heat reflected from the furnace structure directly into the mouth of the nozzle. In the absence of special precautions, this heat is likely to prove extremely damaging to the nozzle. The structure of the present baffle ring 18 is such, however, as to afford a high enough rate of dissipation for the reflected heat, that the nozzle temperature does not build up to a dangerous value. Endurance tests have proved the present nozzle to be capable of withstanding furnace temperatures ranging upward from 2500° F. during many hours of service, while other prior nozzles broke down under the same conditions after less than an hour of service.

From the foregoing, it will be seen that a very effectual, long-life device has been provided. It is, however, one which is extremely simple and economical to manufacture.

I claim as my invention:

1. A blast burner nozzle comprising a metal body portion having a passage extending longitudinally therethrough, said passage being provided with an annular constriction intermediate its ends, the said passage on the approach side of said constriction tapering uniformly from a large inlet to a main port of reduced cross sectional area defined by and extending through said constriction, the discharge end of said main port opening into an enlarged terminal portion of said passage which opens through the end of said body in a discharge orifice greater in cross sectional area than said main port, said passage 25 enlarging being generally circular in cross sectional outline and defined by a circumscribing smoothly curved wall which gradually expands rearwardly from said discharge opening to a point rearwardly of the discharge end of said main port to form an annular groove in said constriction circumscribing the discharge end of said main port, and a plurality of ducts communicating with said passage rearwardly of said constriction, said ducts being inclined outwardly 30 from the axis of said passage in the direction of fluid flow through said ducts, and discharging into said annular groove, the discharge ends of said ducts terminating at the base of said curved wall and being positioned to direct said fluid upon the curved wall surface of said enlarged terminal portion of the passage at points rearwardly of the discharge end of said main port.
- 45 2. A blast burner nozzle described in claim 1, wherein the wall of the nozzle from the region of the bottom of said groove to the discharge end of the nozzle gradually increases in thickness to provide a mass of metal for affording a high rate of heat dissipation.

EDWARD J. HAEDIKE.
